UNITED STATES PATENT OFFICE

KARL AUGUST WAHLBERG AND GUSTAV ADOLF VOLMER WAHLBERG, OF HESSELBY
VILLASTAD, SWEDEN

HANDSAW

Application filed April 28, 1928, Serial No. 273,532, and in Sweden March 28, 1927.

This invention relates to an improvement in such hand-saw frames, which consist of two arms, which are connected by means of a connecting-piece and which on one side of 5 the connecting-piece are provided with a swingably arranged lever intended for the tensioning of the saw-blade.

In the accompanying drawing is shown an embodiment of the invention. Fig. 1 shows 10 from the side a hand-saw frame provided with the improvements according to the invention. Fig. 2 is a section on the line 2—2 in Fig. 1 and Fig. 3 is a section on the line 3—3 in Fig. 1 shown in larger scale. Figure 15 4 is a transverse sectional view taken on lines 4—4 of Figure 1.

In the drawing, 4 indicates the arms provided with the saw-claws 3, which arms are connected by means of the connecting-piece 5. According to the invention the connecting-piece 5 is further provided with a de- 20 5. According to the invention the connecting-piece 5 is further provided with a de- longitudinal grooves 1 (Fig. 3) for holding additional loose saw-blades 2. The connecting-piece 5 is further provided with a de- 25 pression 6, Fig. 3, in which the lever 7 for the tensioning of the saw blade is provided with oppositely disposed eyes 8 at its upper end to receive tensioning wires 9 which are connected at their opposite ends to the arms 4 30 as illustrated in Figures 1 and 4, the lever 7 being swung about the wires to twist them, and thereafter catching its free end in the depression and being held there it thereby prevents the saw-blades in the groove from 35 falling out of them.

The arrangement may of course be modified in several respects within the scope of the invention, and especially the number of the grooves 1 may be varied without deviating 40 from the principle of the invention.

Having now described our invention, what we claim as new and desire to secure by Letters Patent is:

An improvement in hand-saw frames, consisting of two arms connected by means of a connecting-piece, which on one side of the connecting-piece hold the saw-claws and on the other side of the connecting-piece are provided with a swingable lever for the tensioning of the saw-blade, said connecting- 45 50 55 60 65 70 75 80 85 90 95 100

piece being provided with a plurality of longitudinal grooves for holding additional loose saw-blades, said connecting-piece being provided with a depression, in which the free end of the tensioning lever is held, said free end thereby preventing the saw-blades in said grooves from falling out of them.

In witness whereof, we have hereunto signed our names.

KARL AUGUST WAHLBERG.

GUSTAV ADOLF VOLMER WAHLBERG.
